CLAIM

The ornamental design for a wheelchair carrier, as shown and described.

DESCRIPTION

FIG. 1 is a top perspective view of a wheelchair carrier showing my new design;

FIG. 2 is a front elevational view thereof;

FIG. 3 is a left side elevational view thereof;

FIG. 4 is a top plan view thereof;

FIG. 5 is a right side elevational view thereof; and,

FIG. 6 is a rear elevational view thereof.

In the drawings, the broken line showing of external components depicts environmental subject matter and forms no part of the claim.
